UNITED STATES PATENT OFFICE.

HAROLD RUSCHER, OF NEW YORK, N. Y.

CABINET AND CARRIER.

Application filed December 30, 1924. Serial No. 758,911.

This invention relates to ticket cabinets and carriers used in dispensing railroad tickets and similar tickets and has for an object to provide a construction wherein the carrier may be readily applied and removed from the front of the cabinet.

Another object of the invention is to provide a cabinet and carrier for tickets wherein the cabinet is provided with a series of shelves co-acting with a carrier capable of being applied to the shelves from the front of the cabinet.

In the accompanying drawing—

Figure 1 is a fragmentary vertical sectional view through a cabinet with two carriers arranged therein, the same showing one embodiment of the invention.

Figure 2 is a fragmentary front view of the cabinet shown in Figure 1 on a reduced scale, the front door being removed.

Figure 3 is a perspective view of a carrier embodying certain features of the invention, the same being on a reduced scale.

Figure 4 is a sectional view through Figure 3, approximately on line 4—4.

Figure 5 is a fragmentary sectional view through Figure 4 on line 5—5.

Referring to the accompanying drawing by numerals, 1 indicates a cabinet body of any desired kind which is provided with a door 2 at the front adapted to be opened whenever it is desired to remove any tickets from the cabinet. The invention is designed particularly as a cabinet for railroad tickets of a certain variety, namely, tickets that are comparatively long but which may be readily stacked.

In Figure 1, a series of tickets 3 are shown arranged in one of the carriers ready to be removed whenever desired. It will be noted that these tickets extend for almost the full length of the carrier and are stacked flatwise from the bottom of the carrier upward. It is designed to use the cabinet and carriers for tickets of this size or tickets slightly longer or somewhat shorter. Also, in tickets of this kind they are of different widths and, consequently, the carriers have been so formed as to be readily adjustable whereby on any of the shelves 4 any of the carriers may be adjusted to accommodate the particular width of ticket. The shelves 4 are arranged at an appreciable angle and are secured to the side walls of the cabinet body 1 in any desired manner. These shelves

are also preferably of sheet metal whereby the space is reduced to a minimum and whereby the various carriers 5 may be made of sheet metal and readily mounted in position.

In Figures 3 to 5 inclusive, the carriers are shown in detail. From these figures it will be seen that each carrier is provided with a flat bottom member 6, which at one end, is provided with a pressed out hook 7 and at the opposite end with a bent up end structure 8 formed with a turned down section 9 adapted to clamp the upper end of a spring hook 10. If desired, the end 8, section 9 and the upper end of hook 10 may be firmly held together by suitable spot welding, as for instance, the welded section 11. At the front end which carries the hook 7, the bottom 6 is bent up at an angle for forming a front section 12, which front section 75 is again bent for forming a card holder 13, said card holder having pressed out holding pins 14 and a turned over edge 15. The bottom 6 is divided into right and left sections by a central fin or web 16, said fin or web 80 being formed with bent over ends 17 and 18 spot welded to the ends 8 and 12 respectively. The web 16 is also provided with a bottom section 19 suitably spot welded to the bottom 6 as illustrated particularly 85 in Figure 4. This provides a strong stiff construction though the various strips of metal are comparatively thin.

When it is desired to remove one of the carriers 5 from the position shown in Figure 1, the carrier is pulled forwardly until hook 7 is moved out of engagement with the shelf 4 and then swung upwardly and released. This will cause the hook 7 to rest on the upper part of the shelf 4 and permit 95 the carrier to be readily forced to the rear a short distance until hook 10 has been released whereupon the carrier may be raised slightly and then moved out through the front opening of the cabinet, the movement 100 being in a plane substantially parallel to shelf 4. The carrier may be replaced by substantially a reverse movement, namely, the passing of hook 10 over the upper edge of the shelf 4 and pulling the carrier 5 downwardly until hook 7 is allowed to slip over the lower edge of the shelf. The various shelves 4 extend from one side of the cabinet 105 to the other and the carriers 5 are placed thereon at spaced intervals, which intervals 110

may be uniform or may be irregular according to the width of the ticket 3 to be supported.

In Figure 2 it will be noted that the two top carriers 5 are spaced a certain distance apart while the two bottom carriers 5 are spaced a less distance apart. If wider or narrower tickets are to be supported by the carriers, they may be slid readily along the shelf 10 until the desired distance between the web 16 of the respective carriers has been secured. From Figure 1 it will be noted that there is a decided inclination to the shelves 4 and, of course, to the various carriers. This causes the tickets to move by gravity toward the front of the cabinet and to automatically produce a fan structure at the front as they rest against the front wall 12. This slight projection of the front edge of each ticket permits the operator to readily grasp the top ticket and remove the same at any time. It will also be noted that the carriers are comparatively long by reason of the inclination of the shelves and, consequently, tickets of varying lengths may be positioned in the various carriers within the limits of their lengths. It will thus be seen that different length tickets may be stacked flatwise and also tickets having different widths.

What I claim is:

1. A ticket cabinet and carrier, comprising a housing, a shelf arranged in said housing and a carrier mounted on said shelf, said carrier being formed with a hook at the front end adapted to hook over the front edge of said shelf, and a resilient hook at

the rear end adapted to hook over the rear edge of said shelf, said hooks being so engaged that the carrier may be slid longitudinally of the shelf for adjusting the position on the shelf and moved forwardly against the action of said resilient hook sufficiently to release the first mentioned hook. 40

2. In a cabinet, a shelf and a carrier adapted to be removably positioned on said shelf, said carrier comprising a bottom plate formed with a pressed out hook at one end, a dividing web mounted centrally on said plate and extending at right angles thereto, said plate being bent upwardly at both ends and said web being connected to said ends, and a resilient hook at the end opposite the first mentioned hook, said resilient hook being connected to the rear end near the upper edge thereof whereby the resilient hook may be sprung sufficiently to allow the other hook to be passed over the edge of said shelf at any time. 45

3. In a cabinet, a ticket carrier comprising a bottom plate formed with a hook at one end, a dividing web mounted centrally on said plate and extending at right angles thereto, said plate extending upwardly at both ends and said web being connected to said ends, and a resilient hook at the end opposite the first mentioned hook, said resilient hook being connected to the rear end near the upper edge thereof whereby the resilient hook may be sprung to temporarily vary the length of the carrier when the carrier is being mounted in the cabinet. 50 55 60 65 70

HAROLD RUSCHER.
